US0D1044932S

(12) **United States Design Patent** (10) **Patent No.:** **US D1,044,932 S**
(45) **Date of Patent:** ** *Oct. 1, 2024

(54) **PAYMENT TERMINAL**

(71) Applicant: **BANKS AND ACQUIRERS INTERNATIONAL HOLDING, Suresnes (FR)**

(72) Inventor: **Fabien Demange, Fontenay-sous-Bois (FR)**

(*) Notice: This patent is subject to a terminal disclaimer.

(**) Term: **15 Years**

(21) Appl. No.: **35/515,999**

(22) Filed: **Dec. 28, 2022**

(80) **Hague Agreement Data**

Int. Filing Date: **Dec. 28, 2022**

Int. Reg. No.: **DM/226013**

Int. Reg. Date: **Dec. 28, 2022**

Int. Reg. Pub. Date: **Jan. 20, 2023**

CLAIM

The ornamental design for a payment terminal, as shown and described.

DESCRIPTION

1. Payment terminal

1.1 : Front

1.2: Back

1.3 Bottom

1.4: Top

1.5 : Right

1.6: Left

1.7 : Perspective

1.8 : Perspective

The design shows a payment terminal with large screen and keypad.

The broken lines in the drawings depict portions of the payment terminal that form no part of the claimed design.

1 Claim, 8 Drawing Sheets
